UNITED STATES PATENT OFFICE.

ALEXANDER F. HUMPHREY, OF ALLEGHENY, PENNSYLVANIA.

TORPEDO.

SPECIFICATION forming part of Letters Patent No. 747,328, dated December 15, 1903.

Application filed April 30, 1903. Serial No. 155,032. (No model.)

To all whom it may concern:

Be it known that I, ALEXANDER F. HUMPHREY, a citizen of the United States of America, residing at Allegheny, in the county of Allegheny and State of Pennsylvania, have invented certain new and useful Improvements in Torpedoes, of which the following is a specification, reference being had therein to the accompanying drawings.

This invention relates to certain new and useful improvements in torpedoes, and has for its object the construction of a torpedo which may be conveniently suspended from a suitable suspending device and moved through the water on a substantially horizontal line in order to be guided into engagement with the object which it is desired to destroy.

A further object of my invention resides in the construction of a torpedo whereby effective results may be obtained when an explosion occurs.

Briefly described, the invention comprises a shell or body which is adapted to receive the explosive material. This shell or body has exploding means extending into the head thereof and carries on its upper side means for attaching the suspending device thereto. The shell or body carries at its tail end suitable rudders and also has rudders positioned near its forward end, at the sides thereof, which rudders are adapted to be given an inclination which will assist in the guiding of the torpedo through the water.

In describing the invention in detail reference is had to the accompanying drawings, forming a part of this specification, and wherein like numerals of reference indicate like parts throughout the several views, in which—

Figure 1 is a central longitudinal sectional view of my improved torpedo, showing the suspending-cables attached thereto. Fig. 2 is a side elevation of the torpedo with the firing-pin-protecting cap removed. Fig. 3 is a top plan view of the same. Fig. 4 is a longitudinal sectional view of the head of the torpedo, showing the firing apparatus and a part of the fuse.

The torpedo forming the subject of this application is particularly adapted to be used in connection with the form of suspending device such as shown in my application filed

February 2, 1903, Serial No. 141,473. The torpedo involves a shell or casing 1, connected by threading, as at 2, or other suitable means 55 to the head 3. Attached to the rear end of the torpedo shell or body is a tailpiece 4, which may be detachably connected thereto, as shown at 5, or may be made as an integral part of the shell or body 1. In this tailpiece 60 4 is swiveled the rudder 6, and on the sides of the tailpiece are rudders 7, the rear face of which is on a substantially horizontal line with the shell or body and the forward face of which is at an angle to the axial line of 65 said shell or body, and on the sides of the shell or body 1, near the forward end thereof, are rudders 8, which are given a reverse incline to the forward end of the rudders 7. The rudders are inclined in this manner 70 whereby to enable the torpedo to be drawn through the water and maintain the same in a substantially horizontal position, whereby to effectively bring the exploder into engagement with the object to be destroyed. In 75 order that the head 3 of the torpedo may be weakened, whereby not to offer too great resistance to the explosive agent contained by the shell, I preferably provide this head with interior annular grooves 9, into which the explosive agent engages, as seen in Fig. 1. The head 3 has therein a centrally-arranged exterior threaded sleeve 10, in the inner end of which is placed a tube 11, which extends into the shell or body for some distance and is filled 80 with powder to form a fuse for igniting the explosive material within the shell when said explosive material is composed of powder or the like. The powder in this fuse is ignited by means of a percussion-cap 12, exploded by 85 means of a firing-pin 14, extending through the plug 15, threaded in the outer end of the sleeve 10, and which firing-pin is held normally out of engagement with the percussion-cap 12 by means of a spring 16, arranged on 90 the firing-pin between the collar 17, mounted on said pin, and the annular collar or flange 18, carried by the plug 10. Where the explosive agent is powder or the like and a fuse is employed, I dispense with the explosive 95 cap 19 at the inner end of the fuse. If gun-cotton, dynamite, or the like is used as an explosive agent, the same may be exploded through the medium of the percussion-cap 100.

19. The firing-pin carries barbs or points 20, and this, together with the outer end of the firing-pin, is protected by the cap 21, threaded onto the end of the head 3. The shell carries on its upper face eyes 22, to which are attached cables 23 24, both connected at their upper ends to a common ring 25, which is also attached to the cable 26, said cable 26 being connected to a suitable suspending device. (Not shown.) By the manner of supporting the torpedo whereby to maintain the same in a substantially horizontal plan while drawing it through the water, the same may be brought "head on" into engagement with the object to be destroyed, as will be apparent.

15 It will be noted that various slight changes may be made in the details of construction without departing from the general spirit of my invention.

20 Having fully described my invention, what I claim as new, and desire to secure by Letters Patent, is—

25 1. In a torpedo a shell formed of two interlocking sections, one of said sections being formed on its interior with an annular groove, said groove extending to near the outer surface of the said section substantially as and for the purpose specified.

30 2. A torpedo comprising a shell having its forward ends internally screw-threaded and a head formed with exterior threads engaging the threads of said shell, and having its in-

terior formed with a groove, forming a recess in said section extending adjacent the outer surface of the same and a means mounted in 35 said head communicating with the interior of said shell, substantially as and for the purpose specified.

3. In a torpedo, the combination of a shell comprising two interlocking portions, one of 40 said portions having a groove formed in the interior thereof, the inner wall of the groove being near the outer surface of said portion, and an exteriorly-threaded sleeve mounted therein, and means engaging the threads of 45 said sleeve communicating with the interior of the shell to explode the torpedo, substantially as described.

4. A torpedo comprising a shell formed of two interlocking portions, one of said sections 50 having a portion thereof cut away leaving a reduced portion between the outer surface and the interior of the shell, an exteriorly and interiorly threaded sleeve carried in said last-named section, a tube mounted in said sleeve, and means communicating with the interior of the torpedo for firing the same, substantially as described.

In testimony whereof I affix my signature in the presence of two witnesses.

ALEXANDER F. HUMPHREY.
